JOSEPH H. BAIR, OF PHILADELPHIA, PENNSYLVANIA.

RAILROAD-TICKET-PRINTING AUDIT-KEEPING MACHINE.

1,288,470.

Specification of Letters Patent. Patented Dec. 24, 1918.

Application filed October 29, 1917. Serial No. 198,957.

To all whom it may concern:

Be it known that I, JOSEPH H. BAIR, a citizen of the United States, and residing in Philadelphia, Pennsylvania, have invented certain new and useful Improvements in Railroad-Ticket-Printing Audit-Keeping Machines, of which the following, together with the accompanying drawings, is a specification.

10 My invention relates to ticket printing machines and particularly to that class which issues tickets as they are called for and keeps a correct count thereof, in a multiplicity of record dials provided thereon for 15 the purpose, one dial for each destination, and a dial for the total of all fares issued.

The primary object of my invention is to provide a machine for the purpose which is simple and rapid, and which can be so positioned as to cause the ticket vender the least effort in procuring and delivering to 20 the purchaser the desired ticket, and of keeping a record thereof.

To this end I provide a destination selecting mechanism in the form of a disk normally lying in the plane of the slab, or board, at the ticket window, and having a knob by which to turn it, said knob being of suitable form by which to grasp it with 25 the hand and said disk thereon being made preferably of plate glass and having a metallic rim around it to which to attach destination printing plates which distend therefrom radially, said rim or flange being 30 annular, extending downward below the surface of the slab and said destination plates projecting from its lower edge, and being under the window board and free from all obstruction in being whirled 35 around on the disk. Under the selector plate glass disk is a series of destination counters, flat in structure and having a record dial close to the upper edge thereof. These counters are also radially positioned 40 (one for each destination plate) and so tilted as to present the record dials to the best advantage, through the overlying glass disk, to the operator. These counters being extremely light in weight can be mounted 45 on the selector dial inside the metal rim and revolved with it, or be made stationary and free from the selector disk, and an actuator therefor mounted on the rim, the position of which is determined by the destination 50 selected for the ticket to be printed.

I provide a platen, also under the window board, which is stationary, and a movable printing table upon which is the printing form for the ticket, a changeable date, a consecutive numbering device and a place 60 for the destination plate to drop in as the printing table rises to take the impression against the platen. The date plate is removable, and there can be two, so that one can be set for the day ahead while the other 65 is in service.

A plunger also is on the printing table which has on its upper face Half and which normally is below the printing level. By means of a button this is pushed up to the 70 printing level while an impression is made and a half ticket is issued instead of a whole. The counters are capable of counting full fares and half fares on the assumption that a full fare ticket costs twice as 75 much as a half fare. A full fare issue advances its counter one, and a half fare issue only a half. For example, when the counter to New York stands 275 and a full fare ticket is now issued to New York it now stands 80 276. Now a half fare ticket to New York is issued the counter stands 276½. Next again two whole tickets are issued to New York and the counter shows respectively 277½, 278½. Now the total counter is actuated every time a ticket is issued—no matter what the destination. It, too, counts wholes and halves. The number printing machine counts only wholes. So there is always an exact record of the number of 90 tickets issued, the number of fares to each destination and a total number of fares.

The ticket is printed from a roll (which is most economical) and which can be water-marked or specially prepared to meet 95 the requirements of the railroad in question. The ticket is cut off from the strip as it is printed and ejected on the ticket window slab. The selector knob is preferably placed to the left, about in line with the edge of 100 the window, to be actuated by the left hand and the ticket is ejected to the right thereof in line with about the middle of the window. The ejector slot is pitched at a sharp angle away from the operator and toward the 105 purchaser and the ticket is only half way pushed out upon its issue. It can remain there, free from being blown away, until the operator places his thumb back of it and slides it forward toward the purchaser, or 110

the purchaser can reach and get it. The right hand of the operator is free to receive pay and to make change. Great speed can be attained by practising the technique of 5 the transaction.

The printing can be accomplished in two ways; in the larger stations by means of an electric motor and in the smaller stations where power is not available by a foot-pedal. 10 This is the means disclosed in the drawings. Where the former means is availed of, the operation is as follows: turning the selector device to the desired destination then pressing the printing button (there being two 15 buttons—a full fare button and a half-fare one). Both buttons operate the motor, but in addition the half-fare one operates also the half plunger and the actuator so as to register a half instead of a whole number 20 upon the counters involved in the transaction.

My invention also embodies a counter which is capable of counting halves and wholes and which can be arranged in a series, and an actuator common to all so playing upon the counter noting the transaction that when a half ticket is issued it causes it to denote the half and when a whole one is 25 printed it causes it to denote one; and a common counter capable through the actuator to denote each and every whole and half issuing transaction.

The preferred embodiment of the invention is more specifically characterized with 30 reference to the drawings, of which—

Figure I is a plan view of the selective setting up mechanism.

Fig. II is a perpendicular transverse section on the line A—A of Fig. I.

40 Figs. III and IV show the machine in elevation with selected portions in section, of which Fig. IV is a view from the position of the operator with ticket window in background, and Fig. III is a view from the 45 left hand side with the selector disk removed and shews the printing table, paper and ribbon mechanisms with their actuating devices and the ticket cut off. This figure also shows means for locking the machine when 50 the paper roll is used up.

Fig. III^a is a modification of the cam, shown in Fig. III, which cuts off the ticket, and now also causes date to be printed on back of ticket.

55 Fig. III^b is a modification in the inclined face of the platen shown in Fig. III, to include a removable date printing form and an inking ribbon therefor.

Fig. V is a detail perspective view of the 60 paper feed mechanism.

Figs. VI, VII, VIII and IX show the construction of a counter capable of counting units, and halves.

Fig. VI is a longitudinal cross-section of

the counter assembled looking toward upper 65 part, showing the counter wheels in successively lower planes beginning with the units one.

Fig. VII is a plan view of the counter with top cover removed and shows the relation of its wheels to each other in reference to holding, and carrying mechanism.

Fig. VIII is a plan view of counter with top cover on which has dial openings 75 through which the amount is read.

Fig. IX is the bottom cover which is formed, with a flange and ears all around with which to join it to top cover; holes with an annular flange to form bearing for counter wheels and circular race-ways concentric with each hole except last. Both covers are in stair-case steps conforming and confine the several wheels between them.

Figs. X and XI show another flat counter 85 capable of counting units, and halves. The two illustrations show the process of carrying one-half.

Figs. XII, XIII, XIV and XV show a counter having its wheels all on the same 90 axis capable of counting units, and halves. This counter is suitable for recording numbers consecutively and merely registering them.

Fig. XII, A. B. and C. shows the relation 95 between the units and one-half wheel. C. shows the machine clear. B. registering one-half and A. registering one, in the position in the dial indicated.

Fig. XIV, A. and B. show the construction of the "half" wheel of which A. is a plan of its right hand face and B. is a detail of the pawl partly in section.

Fig. XIII is a view of the face (toward the "half" wheel) of the units wheel of the 105 counter, with the housing case surrounding it in section, also showing in broken lines the position, when in place, assembled the race-way in the end piece shown in Fig. XV. Into this race-way extends the end of the 110 pin, fast on the pawl of the "half" wheel, extending through the clearance slot therein.

Fig. XVI is a side elevation of the printing table showing the operation of a selective printing slug, and also the position of 115 the date slug, and a numbering counter with an arm thereon shown in two actuated positions for a unit count and a half count respectively determined by a shiftable cam shown.

Fig. XVII shows the printing form together with selective mechanism and position for the destination plate to drop into.

Fig. XVIII shows the ticket struck from the form on the table with selective slugs not 125 operative.

Fig. XIX shows ticket with slug (good this day only) operative.

Fig. XX is a perspective detail of date slug showing how date is changed from day to day.

In the above drawings 1 is a knob by means of which selective dial σ is turned. This dial has a glass 2, bound by a rim, 3, under which are located and radially disposed counters 4 and distending laterally from the rim (one for each counter) are destination plates 5. The dial σ is mounted rotatably on ball bearings on shaft 6 and hub 55. The dial is lifted, during the printing operation, by means of plunger 7 fast on push rod 8 held in guide 13 and actuated by foot pedal 14. The dial and plunger are supported on arm 54. On top of the push rod is printing table 9, having an opposed platen 10 with its upper face in the plane of table 11, and supported on a pedestal 12. On the table is an operating button 15, which has two cam faces 61 and 62 which actuate push rods 60 and 64 respectively, when the button is depressed against return spring 63, and the half slug 59 in its slot is lifted to the printing level required for printing a half-fare ticket and the pawls 58 and 65 are so positioned that when the printing act takes place the respective counters involved in the transaction have the unit wheels actuated only one notch 68 instead of two thus registering but a half instead of a unit in the dials 67. The pawls 58 and 65 are mounted on the printing table and rise with it to the distance of the platen 10. The plate 5 in the printing position drops into the cutout 5' over which it is superposed at that point of the upward travel of the printing table 9 when the pawls 58 and 65 have carried their respective counter wheels two notches (or teeth 68) of the unit counter wheel 77 thus counting one to the destination for which the ticket is issued. At that point guide lock 57 has slipped its limit into slot 56, and plunger 7 has abutted against shaft 6, and the remainder of the stroke selector disk σ is borne upward to the end, namely to the point where the printing block abuts against the stationary platen. The locking device 56-57 makes it impossible to rotate the selector while the printing block 9 is in the path of the destination plates 5.

Interposed between platen and printing block and above the plane of the destination plates is the ribbon 110 and above it the paper 29. Both paper and ribbon are operated by plunger 8. On the stand 12 is a cross arm 36 and 37. On arm 37, at its end is paper roll 30; at an intermediate point a bearing 46 for paper-feed-arm 17-38. The upper arm 17 is bifurcated and terminated in a slot 19 in which rests a pin 18 on the cage 21 (Fig. V) which is made by the oscillating arm 17 to travel back and forth over the paper holder 16. The cage has a pair of ears 25 on top, and below, in which

are hinged jaws 26 opposed. These jaws travel in the cut out 20 of the paper guide 16. They bite or grip the paper 20 between them feeding it along on the forward movement and open up and slide free on the backward movement. A forward clamp 23 having end bearings 24 in ears 22 rests with its free toothed end (projecting forward, through a slot 28) upon the paper 29 allowing it to feed forward but not backward. The feed is attached to the platen by an angle plate 27.

The lower end 38 of the feed arm terminates in a pin 40 resting in a slot 39 of walking arm 45 hinged at 118 and actuated by means of a pin 117 fastening it to the push rod 8. The other member 44 of the walking beam has at its free end a slot 41 in which rests a pin 42 at the lower end of arm 43-48 hinged at 47 the end of horizontal arm 36. At the upper end it extends into a clearance hole in cut-off block 52 and is hinged to it by means of pin 119. By means of it block 52 is made to move forward and cut off the ticket 51 from paper 29. This shearing block has a guide slot 50 through which extends a guide bar 49. When the rod 8 is pushed up by means of pedal 14, arm 44, of the walking beam, rises and companion arm 45 drops. The slot 39 is so constructed that the paper-cage 21 is quickly pulled back upon the first part of the stroke and remains there until rod 8 partly drops back from the impact position, when it shoots forward feeding the paper and remaining forward at rest. The other arm 48-43 controlled by pin 42 in slot 41 upon the first part of the stroke of push-rod 8 pulls the cut-off block 52 back, opening wide the slot which remains open until close to the end of the return stroke of 8. After the end 29 of the paper roll 30, upon which the ticket was printed is pushed up into the slot by the paper-feed, it closes again and cuts off the ticket 51. This cut-off remains closed during all inactivity of the machine keeping dust, air and moisture from the paper and ribbon, but the ticket is not pinched and can easily be slid out by means of a thumb and finger depression 53.

A safety arrangement is provided to prevent the paper from getting used up before the operator discovers it. If the machine is operated without paper it charges the operator the same as if a ticket were issued, and this should be an incentive to be on his guard; but to avoid the necessity of attending to this the following device is provided. On the paper roll 30 (Fig. III) rests the free end 31 of a lever the other end of which forms a stay for a thrust lever 32 held in tension by push spring 33. As the roll dwindles and lever 31 drops with it the other end is lifted, and finally, above the end of lever 32. At that point the lever 32 shoots

forward and thrusts push rod 34 against rod 8 and when that drops it brings in line therewith a hole 35 into which the pointed end of 34 enters and locks the machine from 5 printing until the machine is loaded with a new paper roll. The idea is to unwind what little paper there is left on the spool; the inner end being gummed, it is united with the outer end of the new roll. It is wound 10 on the roll. The locking device is reset and there is no waste of paper and no bother in threading the paper through the paper feed.

The arms 113—113' actuate the ribbon 15 spools 109—109' respectively by means of their ratchets 111—111'. The ribbon 110 is held in line by means of rollers 112—112'. Only one of the actuating arms 113—113' 20 engages a spool at a time, and that spool only until all the ribbon is unwound therefrom (and on the other) and an arm 114 (held in by the ribbon surrounding it) drops out and as the spool keeps on revolving it abuts against the actuating arm 113 and 25 draws it over, so that the other arm now engages the ratchet on that spool.

The counter 4 preferably used to keep the tally is flat and is shown in Figs. VI to 30 IX inclusive. This counter is extremely light and simple. This counter is capable 35 of counting in halves and wholes and this qualification is highly important in a railroad ticket printing machine as without such a counter the machine would necessarily be twice as complicated.

The wheels 77 are incased between two 40 housing plates 71 and 72. The bottom plate has a hub 66 for each counter wheel. It has a circular carrying pin raceway 69 for each 45 wheel except for the one of highest denomination. It has a spring recess 70. Around it is a flange 74 and ears 75 with which to join it with the companion plate 72. At the units end of both plates is a cut-out 76 to expose two teeth 68 of the units wheel. Each 50 wheel (except the one of highest denomination) has a carrying pin 73 which extends into the plane of the adjacent wheel of next higher denomination. The wheels 77 are held locked and from back lashing by 55 means of a spring 78 one between each two wheels. On the top plate are windows 67 and 67'. These windows are elongated so as to show the figures exposed a half-step 60 movement of the counter wheel. The number wheels have their numbers on the flat face. On the units wheel a "½" is interposed between all the figures but at less distance from the center of the wheel. The 65 window 67' of the units counter has an inward extension in line with the "½" circle (see Figs. VIII, X and XI). It will be seen that by advancing the units wheel one notch at a time alternately "½" will be shown in the units window.

The counter in Figs. X and XI is a modification of that shown in Figs. VI to IX the actuation and windows being the same. The carrying means is different. The units wheel has superposed on the ratchet toothed 70 part 68 a circular disk fast thereto bearing the numbers and halves arranged identically with those of the other counter. The tens wheel has concave faces 80 (one for each number) which conform to the periphery 82 75 of the units wheel and allow it to turn nine tenth of a revolution when the tooth 81 abuts and drops into a recess 79 and carries the tens wheel one step forward to lock the adjacent concave face to the rim of the units 80 wheel. The tens wheel can have fastened to it, in a different plane, a disk like that in the units wheel to actuate a hundreds wheel, and the series can be repeated indefinitely to meet the requirements of the 85 denomination desired. The stepped housing, similar to the other counter, is required. This arrangement is not shown in the drawings.

It is desirable to have the counter which 90 registers all the counting transactions, and keeps a total of all tickets issued of the type where the counter wheels are placed side by side on the same shaft. This counter is stationary and can be more conveniently placed 95 and actuated than the train type preferred for the several destinations. It is also required by several railroads desiring ticket issuing machines to have a printing counter, or ticket numbering device, capable of recording successively, instead of units, the 100 value of the ticket issued. For example, when 700 fares have been issued that number was printed on the last ticket. Should now a "half" ticket be called for the number 105 printed on that ticket will be 700½. If next a "full" ticket is issued its number is 701½, etc. To meet this requirement I have provided the counter shown in Figs. XII to 110 XV inclusive.

On the half wheel is a ratchet 85 similar to that on the units wheel 86. These wheels have number flanges 83 and 84 respectively. The numbers show in a register window 98. If used as a recorder no housing or dial is 115 required. The illustration is in the form of a register instead of recorder. The bearing end support 93 (Fig. XV) has a hole 94 for shaft to rest in, and a race-way 92. This race-way is shown in broken line in 120 the position when assembled (Fig. XIII) in relation to a series of face pins 88 in the face (of units wheel) adjacent to the half wheel. On the "half" wheel, on the units wheel side is a pawl 89 with a cross pin 87 125 at its free end extending through a clearance slot 91. This pin rests in and is controlled by the race-way 92 and the other end extending toward the units wheel plays on the face pins 88 thereon. The counter is 130

mounted on shaft 95, and inclosed and the wheels are held by spring 90. The counter is actuated by an arm 96 having thereon a pawl 97. The "half" wheel has alternately 5 blank spaces and $\frac{1}{2}$ ". As the "half" wheel is rotated by means of the arm 96 in the window 98 are shown (for half wheel) alternately $\frac{1}{2}$ and blank. The tens wheel moves intermittently standing still one space 10 of movement for the "half" wheel and moving a space with the "half" wheel, the units wheel making one revolution to two of that of "half". The carrying connection 15 between units and wheels of higher denomination is not shown as many common methods may be employed.

The ticket 51 printed by the machine herein characterized is shown in Fig. XVIII and one modification thereof in Fig. XIX. 20 This latter one is an excursion ticket. "Good this day only" 100' is put there on the ticket by means of a slug 101 on the printing table Figs. XVII and XVI which is held out of the printing position by a spring 107 and 25 which is made to rise on cams to the printing level by means of a push arm 106. Operative means to include this slug in the printing form is not shown but it is obvious how it can be done. Another modification for 30 the ticket is "half" already described. The ticket Fig. XVII shows the position of the half 59' in dotted lines (one above and half below) with a line between them.

The number 102' placed on tickets can be 35 consecutive, *i. e.* in whole numbers only or it can be a count of the fares in terms of wholes and halves as already described under counters.

The date 100' is printed on the ticket by a 40 form 100 with removable type 104 in a case and spacing slugs 103. This case can be removed to change the date. The date can be put on the back of the ticket instead of where shown, by means of the ticket shearing block 52 if it is so desired. This device 45 is not shown, but in brief consists of a date form resting in platen block 10. The printing impact is made by the forward movement of the shearing block 52 by means of slot 41. In order that this block backs off that the ticket 51 is removable the slot is 50 modified so that a hump 41^a therein is higher than the home end where the pin 42 of the lever 43 remains at rest. The printing block 52, at rest, has backed off from the date type face 110, leaving the ticket 51 free 55 to be withdrawn and free from the inking ribbon 110.

The counter 108, shown in Fig. III, is the 60 improved units and half counter disclosed in Figs. XII to XV. It is mounted together with the printing form like any of the commercial counters but it is actuated by means of an arm 96 thereon which in the upward 65 travel of the printing table 9 on the push

rod 8 abuts by means of a pin 96^a thereon against a lug 60^a on the half determining slide 60, which is controlled by the half button 15. The arm 96 is normally actuated a unit step represented by the arm shown in 70 lower position. When the half key 15 is depressed the lug 60^a is slid in the direction of the arrow and has its lug 60^a out of the path of the pin 96^a which during the impress movement of table is pulled down, to the intermediate position shown and represents a 75 half count. When the table recedes the arm 96 is returned by means of spring 108^b against stop pin 108^c.

Various similar modifications in detail of 80 construction to meet the requirements of the several railroads desiring such a machine may be made without departing from the spirit of the invention.

Although having disclosed the construction of my half and units counters in this specification I do not wish to ask for claims *per se* on them in this application, but will in due time, as the rules of practice allow, ask for such claims under separate application. 90 What I wish to claim herewith is their necessary connection with the railroad ticket machine herein disclosed.

The claims are as follows:

1. In a mechanism of the type described 95 and in combination, a destination selecting device constituting a rotatable disk having radially extending destination printing plates with axially disposed type thereon and a knob wherewith to bring any one of 100 the plates desired into operative position and a printing mechanism.

2. In a mechanism of the type described 105 and in combination, a rotatable destination selecting disk provided with radially extending destination printing plates, a printing table overlapping the plates and having printing form including a plate receiving slot and capable of being impressed on a record together with that of the destination 110 printing plate in operative position and a platen and means for making the impression, said form and disk being arranged for relative movement of translation.

3. In a machine of the class described, 115 and in combination, a destination selecting mechanism consisting of a disk provided with a plurality of radially extending destination printing plates; a plurality of radially disposed counters, a counter for each plate, under said disk and visible through it and means for rotating said disk to bring a selected plate and its counter into operative position.

4. In a machine of the class described, 125 and in combination, a destination selecting mechanism consisting of a disk provided with a plurality of radially extending destination printing plates and means for rotating said disk; a plurality of radially dis- 130

posed destination counters, one for each plate, visible through the disk, to count its printing transactions; a common counter to keep a total of all the printing transactions; means for setting the desired destination plate into the operative position and a mechanism for actuating simultaneously both counters.

5. In a machine of the class described, and in combination, a destination selecting mechanism provided with a plurality of destination printing plates and a complementary plurality of destination counters each adapted to count by units and halves, as desired, 10 and means for setting the desired destination plate and its counters into the operative position.

6. In a machine of the class described, and in combination, a plurality of destination printing plates and a complementary plurality of destination counters each adapted to count by units and halves, as desired, means for setting the desired destination printing plate and its counter into operative position 15 and means for taking the impression and operating the counter.

7. In a machine of the class described, and in combination, a plurality of destination printing plates and a complementary plurality of destination counters each adapted to count by units and halves, as desired; a common counter to operate in consonance with the other counters and to register their total, and means for setting the desired plate 20 and its counter into the operative position.

8. In a mechanism of the class described, and in combination, a plurality of destination printing plates and a complementary plurality of destination counters each adapted to count by units and halves as desired, a common counter to operate in consonance with the other counters and to represent their total; means for setting the desired plate 25 and its counter into the operative position and means for making the impression and operating the counters involved in the transaction.

9. In a mechanism of the class described, and in combination, a series of destination printing plates; a series of destination counters, one for each plate, each adapted to count by units and halves; means for positioning the desired plate and its counter in the operative position; a printing table comprising printing form and platen and means for making the impression and operating the counter involved.

10. In a machine of the class described, and in combination, destination printing plates; destination counters, one for each plate each adapted to count by units and halves as desired; means for placing the desired destination printing plate and its counter into the operative position; a printing table comprising platen and printing form

with selective printing elements therein other than destination plates; manual means for including such elements in the operative form and means for making the impression and actuating the counter involved.

70

11. In a machine of the class described, and in combination, selective destination printing plates; destination counters, one for each plate each adapted to count by units and halves, but normally by units means of placing the desired destination printing plate and its counter into the operative position; a printing table comprising platen and printing form with a shiftable printing slug carrying "half" normally inoperative and means for placing said "half" slug into operative position which also dispositions the counter to count a half.

75

12. In a machine of the class described, and in combination, selective destination printing plates; destination counters, one for each plate each adapted to count by units and halves but normally by units; means for placing the desired destination printing plate and its counter into the operative position; a printing table comprising platen and printing form with a shiftable printing slug, bearing half, normally inoperative; means for placing said "half" slug into operative position which also sets the counter 90 to count a half and means for taking the impression of the form set up and of operating the counter involved.

90

13. In a machine of the class described, and in combination, selective destination printing plates; destination counters, one for each plate; a common counter, all counters adapted to count by units and halves, but normally by units, actuators for counters; means for setting the desired destination plate with its destination counter into operative position and means for setting counter actuators to count a half.

100

14. In a mechanism of the class described, and in combination, selective destination printing plates; destination counters, one for each plate, and a counter common to all plates, all adapted to count by units and halves through the medium of actuators, but normally by units; means for placing any plate and its counter into the operative position; a printing table comprising platen and printing form with a shiftable printing slug, bearing half, normally inoperative and means for placing said "half" slug into operative position which also sets counter actuators to count a half on counters involved when printing of the form set up takes place.

115

15. In a machine of the class described, and in combination, a destination selecting mechanism comprising a plurality of destination printing plates and associated therewith respectively a plurality of destination counters, each adapted to count by units and halves and means for shifting any of the 120

125

130

plates and its counter into the operative position; a common counter to act always in consonance with that destination counter operatively positioned when printing takes 5 place; common actuators for counters involved, which normally actuate them by units when printing takes place, a printing table comprising a platen and a printing form with a shiftable printing slug, normally inoperative, bearing half thereon, and 10 means for shifting said "half" slug into operative position which also sets counter actuators to drive the counter involved a half.

16. In a machine of the character described and in combination, a destination selecting mechanism comprising a plurality of destination printing plates and associated therewith respectively a plurality of destination counters each adapted to count by units 15 and halves, and means for setting any of the plates with its counter into the operative position, a printing adder associated with the printing form to act always in consonance with that destination counter operatively positioned and which progressively 20 records the total of all the destination counters on the printed form; counter and adder drivers which normally actuate the counter positioned and adder by units; a printing table comprising a platen and printing form 25 with a shiftable printing slug, normally inoperative, bearing half thereon; means for shifting said "half" slug into operative position which also sets drivers for counters to 30 add a half and means for actuating printing mechanism and drivers for counters.

17. In a machine of the class described, and in combination, a series of movable printing plates together with a series of 40 counters of which one appertains to each plate and adapted normally, by means of a driver to count by units; a platen and printing form common to all the plates, a "half" printing slug normally omitted but adapted 45 to be included in the printing form; a total adder with driver, normally actuating it by units, appertaining to the printing form; means for shifting any desired destination printing plate and its complementary counter 50 into operative position and manually controlled mechanism for including said slug into the printing form and of dispositioning said drivers of the counter involved and total adder to actuate them by a half.

55 18. In a machine of the class described, and in combination, a series of movable destination recording plates together with a series of destination counters of which one appertains to each plate; a counter common 60 to all the plates; a printing device with printing form common to all the plates and having associated therewith a half printing slug normally omitted but adapted to be included in said printing form; a total adder appertaining to the printing form;

means for shifting any desired destination printing plate with its complementary counter into operative position; drivers for the operative destination counter, for the common counter and for the printing counter actuating each normally by units and manually controlled means for including the "half" slug in the printing form and for dispositioning said drivers to actuate their counters by a half. 75

19. In a machine of the class described and in combination, a plurality of destination printing plates and respectively a plurality of destination counters associated therewith, each counter adapted to count by units and halves and means for bringing any plate with its counter into operative position with respect to the printing mechanism; printing mechanism including a printing form with selective printing elements to issue either a full or a half fare ticket to the destination represented by the plate in the operative position; a common actuator for the counters and operative means to determine whether the form for a full or a half fare ticket shall be set up and whether the counter involved shall be actuated a unit or a half, during the printing act. 80

20. In a machine of the character described and in combination a printing mechanism, a paper feeding mechanism including a paper roll, a plunger element by which said mechanisms are operated, a spring catch tending to lock the plunger element, and a lever actuated by the paper roll and adapted to restrain and free said catch. 90

21. In a machine of the class described, and in combination, a printing mechanism including inking; a paper feeding mechanism; means for operating them and means for locking said parts against operation when the paper roll is substantially exhausted said locking means consisting of a weight arm, of a timing lever, supported on the roll a spring pressed release mechanism 105 with plunger, and a notch in the operating rod to engage it unyieldingly until reset and held open by new roll. 110

22. In a machine of the class described and in combination, a paper feeding mechanism including also a ticket delivery slot having one fixed and one movable wall, and having a removable date-printing form operative in fixed wall; a movable ticket cutting-off block forming the other face wall of the slot by means of which the slot is opened and closed, and adapted to serve as a platen for the date form opposed to stamp date on back of ticket, said block having a cutting edge below to coöperate with fixed edge opposed to cut off ticket and means for operating the block. 115

23. In a machine of the class described, and in combination; a platen; a printing table having ticket form and a vacant space 130

- thereon to be occupied by the destination plate selected to complete the type form for the ticket and said printing table adapted to be moved against said platen when printing; 5 paper and inking ribbon under said platen; a series of destination plates radially extending from a rotatable disk axially movable also, having turning means adapted to sweep the plates over the table and place any one 10 thereof in position over the vacant space provided in the printing form and means to lift the printing table first to meet the superimposed plate and then to carry it along with the form together with the rotatable, 15 axially movable disk constituting the selector, to which it is rigidly attached, to the printing level.
24. In a machine of the character described, and in combination, a platen; a 20 printing table provided with a printing form and a vacant space therein, adapted to be occupied by a destination plate to complete the ticket form, and said printing table having counter actuating mechanism associated therewith, adapted to move with it when printing; a series of destination printing plates radially extending from a rotatable disk, axially movable also, and having turning means thereon adapted to sweep the 25 plates over the table to place any one thereof in position over the vacant space provided in the printing form; a series of destination counters, one for each plate in fixed relation 30 to it, under the disk and readable through it,
- and means to lift the printing table against 35 the platen to print, in which movement it first rises to place the superimposed plate in the type form, which period constitutes the lost motion between selector disk, with plates and counters thereon, and printing 40 table, and during which the actuator advances the counter, then all are lifted *en masse* until type strikes platen.
25. In a machine of the class described, and in combination, a printing mechanism 45 including a selective printing form of which one element is a "Good this day only" printing slug or its equivalent which element is normally inoperative but with means for including it operatively; a series of destination printing plates and selective means to make any one such plate operative with the printing form; a series of destination counters, one for each destination plate except for places to which there are frequent 50 excursions two counters for each plate of which one is normally inoperative when its plate is operative for regular tickets but adapted to be made operative when the "Good this day only" slug is operative, a 55 driver to actuate the counter of the plate operative and means for including operatively the "Good this day only" slug and of shifting the driver so as to actuate the excursion ticket counter instead of the regular ticket 60 counter of the destination printed with the ticket form.
